UNITED STATES PATENT OFFICE.

WILLIAM C. DUNN, OF LOGANSPORT, INDIANA.

BICYCLE.

SPECIFICATION forming part of Letters Patent No. 655,697, dated August 14, 1900.

Application filed November 11, 1899. Serial No. 736,716. (No model.)

To all whom it may concern:

Be it known that I, WILLIAM C. DUNN, a citizen of the United States, residing at Logansport, in the county of Cass and State of Indiana, have invented certain new and useful improvements in Bicycles; and I do hereby declare the following to be a full, clear, and exact description of the invention, such as will enable others skilled in the art to which it applies to make and use the same.

This invention relates to certain new and useful improvements in bicycles of the chainless type, and more particularly to that class of chainless wheels in which bevel-gears are employed.

It has for its objects, among others, to provide an improved construction in which the parts shall be compactly arranged and disposed in a novel manner, the three gears being all about the one center. The crank-axle and the intermediate gear being made at a certain angle and placed on another bearing of a certain angle gives opportunity of getting any gearing desired. The intermediate gear has its bearing on a stud or projection on the frame which incloses the crank-axle. The gears are all inclosed within the hub of the wheel through which the crank-axle passes. The cranks are connected to rods or levers at points one side of their longitudinal centers, and the rear ends of these rods or levers are pivotally connected to arms that in turn are pivoted to projections on the frame below the axis to constitute pulls on the rods or levers.

Other objects and advantages of the invention will hereinafter appear, and the novel features thereof will be specifically defined by the appended claim.

The invention is clearly illustrated in the accompanying drawings, which, with the letters of reference marked thereon, form a part of this specification, and in which—

Figure 1 is an elevation of a bicycle embodying my present invention. Fig. 2 is an enlarged substantially-central section through the hub of the gear-wheel.

Like letters of reference indicate like parts throughout the different views.

Referring now to the details of the drawings by letter, A designates the crank-axle, having the cranks *a*, as seen clearly in Fig. 2.

B is a bevel-gear secured to the crank-axle in any of the well-known ways.

C is the frame of the bicycle, in which the crank-axle has ball-bearings of known construction, as seen at *c c*.

D is a sleeve supported at one end on the frame C, as shown best in Fig. 2, and surrounding the axle A for a greater portion of the length of the latter. This sleeve performs important functions, as will hereinafter appear. It is exteriorly screw-threaded near its outer end, as seen at *d*, to receive the adjustable cone E for the ball-bearing F of the bevel-gear G, which is fast with the hub H of the rear wheel, which carries a casing *h* or hub, to which the spokes *I* are attached. The inner end of this sleeve has an angularly-disposed bearing *j* for the balls *J* of the intermediate gear K, which is provided with the gear-teeth *k*, set at an angle, as shown, and meshing with the bevel-gear B, while at the opposite edge of the intermediate gear are the teeth *k'*, which mesh with the gear G, as clearly shown in Fig. 2. It will thus be seen that gear B is fast upon the axle, gear K has a bearing concentric with, but independent of, the said axle, and gear G has a bearing concentric with, but independent of, the axle, and gear B imparts its motion to gear K, which in turn transmits power to the gear G and to the rear wheel.

The outer ends of the cranks are connected to the levers L at the points *l*, which is preferably three-tenths from the rear end of the said levers. The rear end of each lever is pivotally connected, as at M, to the rod N, the other end of which is pivotally connected, as at O, with the projection or arm P on the lower longitudinal bar of the bicycle-frame and braced by the brace Q, all as clearly shown in Fig. 1, it being understood that there is a lever, rod, and arm on each side of the machine.

With the parts arranged as above described the operation will be readily understood, and a detailed description thereof is not deemed necessary.

The teeth will be shaped with sufficient play to allow for the angular disposition of the intermediate gear, as will be readily understood.

It is deemed important that the sleeve be

of larger interior diameter than the crank-
axle, so that the latter will be held out of
contact therewith throughout the length of
the sleeve, and thus the frictional contact of
5 these parts prevented.

What I claim as new is—

The combination with the crank-axle, the
sleeve eccentric therewith and held out of con-
tact therewith, and having inclined ball-bear-
10 ing surrounding the same, of a gear fast upon
said axle, a hub, a gear movable therewith,
and a gear having an inclined ball-bearing on

the said inclined bearing of the sleeve and
having angularly-disposed teeth upon its op-
posite faces to mesh directly with the gears on 15
the axle and hub whereby rotation of the axle
imparts a rotary movement to said hub, as set
forth.

In testimony whereof I affix my signature
in presence of two witnesses.

WILLIAM C. DUNN.
